UNITED STATES PATENT OFFICE

128,936

DESIGN FOR A CAPSULE CONTAINER AND DISPENSER

John B. Foley, Chicago, Ill.

Application April 17, 1941, Serial No. 100,479

Term of patent 14 years

To all whom it may concern:

Be it known that I, John B. Foley, a citizen of the United States of America, residing at Chicago, Illinois, have invented a new, original, and ornamental Design for a Capsule Container and Dispenser, of which the following is a specification, reference being had to the accompanying drawing, forming a part thereof.

Fig. 1 is a perspective view, Fig. 2 a side elevational view, Fig. 3 a top plan view in closed position, Fig. 4 a top plan view in open position, and Fig. 5 is a bottom plan view of a capsule

container and dispenser embodying my new design.

In my capsule container and dispenser the cylinder, the inverted cone therein and the double closure are of transparent material. The bottom portion is opaque.

I claim:

The ornamental design for a capsule container and dispenser, substantially as shown and described.

JOHN B. FOLEY.
